UNITED STATES PATENT OFFICE

LOUIS TOMANEK, OF CHICAGO, ILLINOIS

WELL DRILL

Application filed September 4, 1930. Serial No. 479,673.

This invention has for its object to provide a novel and efficient deep-well drill of simple construction and easily operable in substantially the ordinary way common to devices of this character to effect drilling through all types of geological formations ordinarily encountered in drilling for oil, gas, or water.

In the accompanying drawings illustrating the invention:

10 Fig. 1 is a vertical sectional view of a pipe lined drill hole in course of being extended to greater depth by means of a drill constructed in accordance with this invention.

15 Fig. 2 is an enlarged vertical sectional view of the pipe and the drill of the present invention disposed therein and illustrating details of construction of the latter.

Fig. 3 is a bottom plan view of the drill.

The drill of this invention comprises a cylindrical head 1 preferably integral with a point element 2, the element 2 being tapered and of appreciably smaller diameter at its upper and larger end than said head 1. Between its ends said point element 2 is provided with a series of longitudinal recesses 3 alternating with longitudinal ribs 4 having sharp side edges 5 which partly overhang the recesses 3. The latter are spaced appreciably from the lower extremity of said point element 2 which is flat bottomed.

At the other or upper end of the head 1, there is provided a shank 6 which is externally threaded to engage in the threaded socket of the cylindrical block 7. The latter and the drill element 1-2, are provided with axial bores 8 and 9, respectively, communicating with each other. The upper end portion of the bore 8 is threaded to receive and engage the eye-bolt 10 by means of which the block 7 and drill element 1-2 are suspended from the cable 11 or other element by means of which said drill element may be reciprocated.

In the block 7 there is provided an inclined bore which communicates at its lower end with the bore 8 of said block and is adapted to be suitably connected at its upper end with a tube or pipe 13.

The drill element and block 7 are preferably disposed within a pipe 14 of slightly

greater diameter than the head 1 and block 7 so as to provide a free annular space about the last mentioned elements.

In operation, the lower end of the pipe 14 is set upon the ground concentric with the proposed drill-hole and the drill assembly is thereupon reciprocated in such manner that, after being raised, it will drop by gravity to impart consecutive blows which will serve to cause the lower end of point element 2 to crush and pulverize rock or displace softer material. As said point element penetrates the earth to a depth sufficient to bring the ribs 4 into contact with the material to be removed, the sharp side edges 5 of said ribs will cut into the same to remove it gradually, all material encountered being comminuted by the action of the drill element.

This comminuted material is preferably removed by means of fluid under pressure, 70 preferably water, supplied from a suitable source through the pipe 13, this fluid serving to carry the comminuted material up through the space between the head 1 and the pipe 14.

The pipe 14 constitutes a guide for the drill assembly which, in practice, rotates slowly or is rotated slowly during reciprocation either automatically or by force suitably exerted upon the suspension element 80 11, the pipe 14 being forced downwardly at intervals to cause it to break down the material in its path which may not be broken away by the drill assembly.

Practice has demonstrated that if element 85 11 consists of a rope or cable, the drill assembly will automatically rotate during reciprocation so that the sharp edges 5 of the ribs 4 will seldom strike twice in the same place during consecutive strokes. The drill assembly will also become slightly canted or will wobble about its longitudinal axis so that the drill hole produced thereby will be of appreciably greater diameter than the cylindrical portion 1 which operates below 90 the lower end of the pipe 14 so that the latter may be quite readily lowered at intervals.

I claim as my invention:

1. A well drill head comprising an integral member having a cylindrical upper end por-

tion and a tapered point portion constituting an inverted truncated cone, said point portion being provided with a plurality of longitudinal recesses having their lower ends spaced from the lower extremity of said head and having their upper ends disposed substantially flush with the lower end of the cylindrical portion, said recesses defining a series of ribs having sharp side edges.

10 2. A drill head comprising an integral member having a cylindrical upper end portion and a tapered point portion constituting an inverted truncated cone, the base of which corresponds in diameter with said cylindrical portion, said point portion equipped with a series of longitudinal recesses spaced from the lower extremity of said point portion and terminating substantially at the lower end of said cylindrical portion, said recesses defining a series of ribs having sharp, parallel side edges extending coincidentally with said recesses.

15 3. A drill head comprising an integral member having a cylindrical upper end portion and a tapered point portion constituting an inverted truncated cone, the base of which corresponds in diameter with said cylindrical portion, said point portion equipped with a series of longitudinal recesses spaced from the lower extremity of said point portion and terminating substantially at the lower end of said cylindrical portion, said recesses defining a series of ribs having sharp, parallel side edges extending coincidentally with said recesses, the said side edges of said ribs being sharp and overhanging the mouths of said recesses.

35 In testimony whereof, I have hereunto set my hand this 2nd day of September, 1930.

LOUIS TOMANEK.
